ATTORNEY

UNITED STATES PATENT OFFICE.

FRANK M. NORRIS, OF LOS ANGELES, CALIFORNIA.

IGNITION SYSTEM.

1,269,495.

Specification of Letters Patent. Patented June 11, 1918.

Application filed January 17, 1917. Serial No. 142,907.

To all whom it may concern:

Be it known that I, FRANK M. NORRIS, a citizen of the United States, residing at Los Angeles, in the county of Los Angeles and

5 State of California, have invented new and useful Improvements in Ignition Systems, of which the following is a specification.

This invention relates to improvements in mechanism for igniting the charge in internal combustion engines, and more particularly to those engines to which the method of ignition known as "jump spark" or "high tension" ignition is applied.

The primary object of this invention is 15 to provide a simple, substantial, and efficient means of conveying the ignition current to the spark plug or plugs of internal combustion engines, thereby eliminating the numerous disadvantages which have been 20 found to occur where a multiplicity of small separable insulated conductors is used.

Another object is to provide an efficient means for varying the time of occurrence of the spark or sparks relatively to the cycle 25 of operations within the cylinder or cylinders so that the spark may be advanced or retarded as the varying speed of the engine or other conditions may require.

A still further object is to provide a mechanism which may be easily and quickly dismounted and remounted for purposes of examination, replacement, or repair; or to permit examination, replacement, repair or cleaning of any spark plug.

35 A fourth object is to provide a mechanism which may be used to drive a magneto or other generator, which may be attached thereto, and may thereby establish electrical connection with such generator, and in this 40 manner eliminate the necessity for any wiring whatsoever between the generator and spark plugs.

These objects and others which are embodied in the appended claims, and which 45 will make themselves apparent from the accompanying description to those versed in the art of ignition in internal combustion engines, are obtained by the use of mechanism substantially as hereinafter described 50 and specified, reference being had to the accompanying drawings.

In the drawings:—

Figure 1 is a side view of my ignition mechanism as applied to the engine of an 55 automobile having four cylinders, but it is obvious that it is equally applicable to an

internal combustion engine having any number of cylinders and of any type using high tension electricity as the means of igniting the charge.

Fig. 2 is a detail view of the means of connecting the wire conveying the high tensioned electrical current from the generator, induction coil, or other source with the rotating portion of the mechanism.

Fig. 3 is a detail view of a portion of the mechanism which may be used to alter the time of the occurrence of the spark relatively to the cycle of operations within each cylinder.

Fig. 4 is a side view of the means of conveying electric current from the principal conducting portion of the mechanism to the proper electrodes of the spark plugs.

Fig. 5 illustrates the use of this device for 75 directly driving the magneto or other generator.

All parts are numbered alike throughout the drawings. Referring now to the drawings in detail, A, B, C and D designate the 80 cylinders of an automobile engine, which is here used for the purpose of illustrating the construction and operation of this device. 1 designates a rotating shaft of metal or other conducting substance, properly 85 mounted relatively to the cylinders A, B, C and D and journaled in bearings 2, which bearings may or may not have removable caps, and which are properly insulated from the frame of the engine. 3 is a disk 90

of insulating material securely keyed or otherwise fastened to the shaft 1 in such a manner as to rotate therewith, one of these disks being provided for each spark plug of the engine, and so placed on the shaft 1 that 95

its circumference will revolve in close proximity to or in contact with an electrode 4 of the spark plug or to an extension thereof or to a contact member 5, which is pressed firmly against the circumference of the disk 100

3 by a spring 6. Embedded within the circumference of the disk 3 is a segment of metal of other conducting material 7, this segment being electrically connected with the shaft 1. At one end of the shaft 1 is 105 mounted an insulated holder 8, which contains a contact member 9 which is pressed into a similarly shaped depression in the end of the shaft 1 by a spring 10, also inclosed within the holder 8. The contact member 9

110 has attached thereto a wire 11 connecting it with a generator 12, furnishing the igni-

tion current. It is further provided with a knob 13 projecting through a slot in the housing 8, by which means the contact member 9 may be withdrawn from the depression into which it is forced, thereby facilitating the removal of the shaft 1 when required.

At the opposite end of the shaft 1 is mounted a device 14 for varying the timing 10 of the spark relatively to the cycle of operations within the cylinders A, B, C and D. This device 14 consists of a slideable sleeve 15 uniting the shaft 1 with a continuation 16 thereof. The end of this sleeve 15 which 15 telescopes on the end of the shaft 1 is provided with spiral slots 17, through each of which slots projects a pin 18 secured to the shaft 1. The opposite end of the sleeve 15 is provided with a straight slot 19 parallel 20 to the axis of the sleeve and having projecting therethrough a pin 20, which is secured to the shaft 16. Around the circumference of this sleeve extends a groove 21 into which extends one end of the lever 22, which is 25 connected with the proper hand lever on the steering column of the automobile. By moving this lever, the sleeve 15 may be shifted endwise on the shafts 1 and 16, thereby altering their relative positions. At the opposite 30 end of the shaft 16 is mounted a means of transmitting power to the shaft 16 from some rotating portion of the engine, such means being here shown as a bevel gear 23.

In practice, the shafts 1 and 16 will be 35 driven through the gear 23 at such a ratio to the speed of the engine that the segment 7 will coincide with the contact member 5 at the instant during each cycle of operations within a cylinder at which the compressed 40 charge should be ignited. By this means the current completes the circuit through the spark plug thereby igniting the charge.

I may modify the arrangement shown herein, as illustrated in Fig. 5 of the drawings, in which figure a generator 24 or other 45 source of ignition current is suitably mounted upon and insulated from a bracket 25 in place of the insulated holder and inclosed parts 8, 9 and 10, as shown in the previous 50 figures, the shaft of the generator 24 being driven by the shaft 1, with which it establishes good electrical connection. One terminal of the generator windings is suitably connected to the generator shaft, and the 55 other terminal is properly connected with some portion of the engine frame, in this instance the bracket 25. The operation when this combination of features is used is obvious. The current flows directly from the 60 generator into the shaft 1, the segment 7, and the contact member 5 of the spark plug without any wiring whatsoever.

From the foregoing description taken in 65 connection with the accompanying drawings, the various advantages of the mecha-

nism will make themselves apparent to those familiar with the art, but I wish to call attention to the fact that by removing the caps of the bearings 2 and withdrawing the contact member 9, the shaft 1 may be instantly 70 removed and examined, and repaired if necessary, and any spark plug may then be easily and quickly removed and examined or any necessary changes made.

While I have herein shown and described 75 the preferred form of my invention by way of illustration, I wish it to be understood that I do not limit or confine myself to the precise details of construction herein described and delineated, as modification and 80 variation may be made within the scope of the claims and without departing from the spirit of the invention.

I claim:—

1. In an ignition mechanism for engines 85 having spark plugs, a shaft, means for attaching said shaft of an engine in proximity to a spark plug of the engine, means carried by the shaft whereby the spark plug of the engine will be energized at a predetermined 90 point in the rotation of the shaft, a drive shaft for the first-mentioned shaft, a sleeve on said shafts formed adjacent one of the shafts with a longitudinal slot and formed adjacent the other shaft with a spiral slot, 95 each shaft having a portion engaged in the respective slot, a means for moving said sleeve longitudinally of said shafts, a spring pressed plunger having means whereby it is engaged with the first mentioned shaft, 100 and means for electrically energizing said plunger.

2. In an ignition mechanism for engines having spark plugs, a shaft, means for attaching said shaft of an engine in proximity 105 to a spark plug of the engine, means carried by the shaft whereby the spark plug of the engine will be energized at a predetermined point in the rotation of the shaft, a drive shaft for the first-mentioned shaft, a sleeve 110 on said shafts formed adjacent one of the shafts with a longitudinal slot and formed adjacent the other shaft with a spiral slot, each shaft having a portion engaged in the respective slot, a means for moving said 115 sleeve longitudinally of said shafts, a spring pressed plunger having means whereby it is engaged with the first mentioned shaft, a means for electrically energizing said plunger, and means for manually disengaging 120 said plunger from the first mentioned shaft.

3. An ignition mechanism for internal combustion engines having a plurality of spark plugs, comprising a rotatable insulated shaft of conducting material, provided at one end with means of connection to a source of electricity, this means consisting of a spring-operated contact member engaging a depression in the end of the shaft, 125 said contact member being provided with a 130

projecting portion facilitating withdrawal from said depression, said shaft having secured thereto a plurality of disks of insulating material equal in number to the spark 5 plugs of the engine, and so arranged as to rotate with the shaft with the circumference of each disk in juxtaposition to the terminal of the corresponding spark plug, each disk being provided with a conducting segment 10 electrically connected with said shaft, means for electrically energizing the shaft, and means for rotating the same.

4. An ignition mechanism for internal combustion engines having a plurality of 15 spark plugs, comprising a rotatable insulated shaft of conducting material, journaled in bearings having removable caps, provided at one end with means of connection to a source of electricity, this means 20 consisting of a spring-operated contact member engaging a depression in the end of the shaft, said contact member being provided with a projecting portion facilitating withdrawal from said depression, said shaft 25 having secured thereto a plurality of disks of insulating material equal in number to the spark plugs of the engine, and so arranged as to rotate with the shaft with the circumference of each disk in juxtaposition 30 to the terminal of the corresponding spark plug, each disk being provided with a conducting segment electrically connected with said shaft, means for electrically energizing the shaft, and means for rotating the 35 same.

5. An ignition mechanism for internal combustion engines having a plurality of spark plugs, comprising a rotatable insulated shaft of conducting material, journaled in bearings having removable caps, provided at one end with means of connection to a source of electricity, this means 40 consisting of a spring-operated contact member engaging a depression in the end of the shaft, said contact member being provided with a projecting portion facilitating with- 45

drawal from said depression, said shaft having secured thereto a plurality of disks of insulating material equal in number to the spark plugs of the engine, and so arranged 50 as to rotate with the shaft with the circumference of each disk in juxtaposition to the terminal of the corresponding spark plug, each disk being provided with a conducting segment electrically connected with said 55 shaft, means for electrically energizing the shaft, means for rotating the same, and means for adjusting said shaft while rotating so as to vary the time of coincidence of the conducting segments with the corresponding spark plug terminals or extensions 60 thereof.

6. In an ignition mechanism for engines having spark plugs, a shaft, means for attaching said shaft to an engine in proximity 65 to a spark plug of the engine, means for electrically energizing the shaft, means carried by the shaft whereby the spark plug of the engine will be energized at a predetermined point in the rotation of the shaft, 70 a drive shaft for the first-mentioned shaft, a sleeve on said shafts formed adjacent one of the shafts with a longitudinal slot and formed adjacent the other shaft with a spiral slot, each shaft having a portion engaged 75 in the respective slot, and means for moving said sleeve longitudinally of said shafts.

7. In an ignition mechanism for engines having spark plugs, a shaft, means for attaching said shaft to an engine in proximity 80 to a spark plug of the engine, means for rotating the shaft, means for electrically energizing the shaft, means carried by the shaft whereby the spark plug of the engine will be energized at a predetermined point in the 85 rotation of the shaft, said shaft being formed in at one end with a recess; and a plunger adapted to enter said recess and also adapted to be manually disengaged from said recess. 90

In testimony whereof I affix my signature.
FRANK M. NORRIS.
